(57) **CLAIM**

The ornamental design for a bicycle axle nut, as shown and described.

DESCRIPTION

This application is related to U.S. patent application Ser. No. 29/529,126 filed Jun. 4, 2015.

FIG. 1 is an oblique view of a bicycle axle nut showing our new design;

FIG. 2 is a side elevation view showing the front side thereof;

FIG. 3 is a side elevation view showing the left side thereof;

FIG. 4 is a side elevation view showing the rear thereof;

FIG. 5 is a side elevation view showing the right side thereof;

FIG. 6 is a top plan view thereof; and,

FIG. 7 is a bottom plan view thereof.

The broken lines shown illustrate portions of the bicycle axle nut that form no part of the claimed design.
